UNITED STATES PATENT OFFICE.

BERTHOLD WEINBERG, OF NEW YORK, N. Y.

COUCH.

No. 834,501.

Specification of Letters Patent.

Patented Oct. 30, 1906.

Application filed March 30, 1906. Serial No. 308,998.

To all whom it may concern:

Be it known that I, BERTHOLD WEINBERG, a subject of the German Emperor, residing at New York city, in the county of New York and State of New York, have invented 5 certain new and useful Improvements in Couches, of which the following is a specification.

The present invention pertains to a couch, 10 and has for its object to simplify the construction thereof and to provide the same with a spring-mattress, so as to dispense with any other cushioning means.

The arrangement of the mattress forms the 15 main feature of the present invention, and I wish to reserve the right to use this mattress not only with the couch in connection with which it is shown and described, but also separately for beds, chairs, or the like.

20 The invention is illustrated in the accompanying drawings, in which similar reference-letters denote corresponding parts, and in which—

Figure 1. is a side elevation of my couch; 25 Fig. 2, a plan view thereof; Fig. 3, a rear view thereof. Figs. 4 and 5 show details of the mattress.

The couch consists of a frame formed of a 30 U-shaped rail *a*, to which one pair of legs *b* is attached by means of ordinary elbow-joints *c*, and of a frame *d*, the upper part of which may be bent rearward to form the head part and the lower part of which forms the second pair of legs *e*. This frame *d* is secured to the 35 frame *a* by similar elbow-joints *c*. Over the longitudinal rails of the frame *a* and the head part of the frame *d* an ordinary wire-netting *f* is stretched. The upper part of the wire-netting stretched over the head-frame may 40 be attached to coil-springs *g*, suspended from the transversal piece of the frame *d*.

Interwoven with the meshes of the base-netting *f* are upwardly-projecting spiral springs *h*, which preferably are made wider at 45 their top and narrower at their bottom. On

top of the springs *h* a stuffed mattress *i*, a cover, or a wire-netting may be placed. The springs are constructed as follows: The lower end of the spiral spring *h* is extended in form of a tail *k* and is bent zigzag to correspond 50 with the bending of the meshes of the wire-netting and is provided with a hook *l*. The springs are placed to rest upon the knots *j* of the meshes. The tail of the spring is interwoven with the meshes and connected with 55 the neighbor spring by means of the hooks *l*.

Instead of using single springs double springs *m* can be arranged of an integral piece of wire. The connecting-piece *n* of the double spring is also bent zigzag similarly to 60 the tail of the single spring to correspond with the meshes of the wire-netting and to allow of it being interwoven with the meshes of the latter. In the example shown I use single and double springs, arranging one dou- 65 ble spring at one end of each transversal row and connecting the same at its bottom with the single springs of the same row or with those of the longitudinal row.

The upper ends of the springs of the vari- 70 ous rows may be connected with each other by wire pieces, chains, or the like to hold the springs in upright position.

What I claim, and desire to secure by Letters Patent, is—

75 The combination with a frame, of a wire-netting and spiral springs interwoven with the meshes of the latter, the bottom end of said springs being extended and bent zigzag to correspond with the meshes of the netting, 80 a hook formed at the free end of said extended part, to allow the connection of the individual springs with each other, substantially as and for the purpose specified.

In testimony whereof I affix my signature 85 in presence of two witnesses.

BERTHOLD WEINBERG.
